WILTON F. JENKINS AND ROBERT L. JENKINS, OF RICHMOND, VIRGINIA.

FUEL-MIXING DEVICE FOR INTERNAL-COMBUSTION ENGINES.

1,132,351.

Specification of Letters Patent.

Patented Mar. 16, 1915.

Application filed September 25, 1913. Serial No. 791,801.

To all whom it may concern:

Be it known that we, WILTON F. JENKINS and ROBERT L. JENKINS, citizens of the United States, and residents of Richmond, in the county of Henrico and State of Virginia, have invented certain new and useful Improvements in Fuel-Mixing Devices for Internal-Combustion Engines, of which the following is a specification.

10 Our invention relates to improvements in fuel mixing devices for internal combustion engines, and it consists in the combinations, constructions, and arrangements herein described and claimed.

15 An object of our invention is to provide a device by means of which the fuel of internal combustion engines may be thoroughly mixed before entering the combustion chamber.

20 A further object of our invention is to provide a device which may be readily applied to the intake manifold of internal combustion engines on any standard make of automobile without necessitating any 25 change whatever in the number or shape of the parts of the apparatus to which the device is to be applied.

25 A further object of our invention is to provide a device for mixing the fuel which 30 may be used in connection with any suitable form of carburetor and which results in such a complete mixture of the air and fuel that much less fuel is required for a given amount of power than where the mixing device is not used.

35 A further object of our invention is to provide a device which is simple in its nature, cheap to manufacture, and which will not easily get out of order.

40 Our invention is illustrated in the accompanying drawings forming part of this application in which—

Figure 1 is a side view of an engine provided with our improved mixing device, 45 Fig. 2 is a section through the end of the intake manifold showing the mixing device in position, and Fig. 3 is a section along the line 3—3 of Fig. 2.

50 Referring now to the drawings 1 denotes in general an engine having the usual intake manifold 2 leading to the cylinders. The lower end of this manifold is provided with the usual flange 3, which is connected to a similar flange 4 on the outlet pipe 5 leading 55 from the carburetor 6. A gasket 7 is provided between the flanges 3 and 4, shown

in Fig. 2, and these flanges are held together by means of bolts 8. The construction thus far is ordinary and forms no part of our invention except in so far as the 60 parts coöperate to hold the mixing device, as will be explained.

The mixing device proper consists of a cylindrical member 9 of metal or other suitable material which has an upper tapered end 10 provided with perforations 10^x. It will be noted that these perforations are at right angles to the axis of the cylinder 9. A downwardly extending integral portion 11 is provided with similar perforations 10^x 65 also extending at right angles to the axis of the cylinder. This inner part 11 is provided for the purpose of affording additional means of escape for the fuel, and while at the same time taking up less room 70 than if extended on beyond the end of the portion 10. At each end of the cylindrical portion 9 is disposed a spider 12 which is held in place by screws 13 extending through the wall of the cylindrical portion. 75 Disposed between the spiders is a shaft 14 80 whose ends are secured in the spiders 12. Rotatably mounted on the shaft 14 are the hubs 15 and 16 of propellers whose blades 15^x and 16^x respectively are turned in opposite directions. That is to say, the lower propeller will revolve in one direction and the upper propeller in another. The propeller hubs are spaced from the spiders by washers 17, while a central washer 18 is disposed between the hubs 15 and 16. 85 90

From the foregoing description of the various parts of the device the operation thereof may be readily understood.

In attaching the mixing device the bolts 95 are withdrawn from the flanges 3 and 4 and the mixing device is thrust up into the lower end of the intake manifold 2, the flange 9^x being seated against the packing 7 on one side and being arranged to bear against the 100 upper flange 3 on the other. The flange 9^x is made thin so as to permit the packing 7 to assume substantially its normal position when the bolts 8 are again tightened up. When the device is attached it has the appearance and position shown in Fig. 2. 105

Now when the engine is cranked and starts up the suction will draw the fuel through the carburetor in the usual manner. It will then pass through the outlet pipe into 110 the mixer. The force of the moving fuel will cause the propellers to revolve in oppo-

site directions, as heretofore stated, thus thoroughly mixing the fuel and air. The mixture will then pass through the openings 10*. The openings in the portion 11 5 being directed toward each other will cause a further mixture of the fuel, while the openings which are in the conical part 10 will permit the fuel to be forced into contact with the walls of the manifold 2 thus 10 mixing the fuel on this side. The result is that the fuel is thoroughly mixed and when ignited will be almost entirely consumed.

In actual tests we have found that fifty per cent. of fuel is saved by the device over 15 that saved when the device is used with the ordinary carbureter. The saving of fuel is not the only result of the thorough mixture of the fuel with the air. Besides giving greater power in proportion to the fuel consumed the combustion is more complete, and therefore there is very little carbon deposit 20 in the cylinder, or in the other working parts of the engine. This results in greater efficiency of the engine and requires less tearing down of the motor to rid the same of 25 carbon than when the mixer is not used.

Intake manifolds are ordinarily made in one of five sizes and the mixing device would be made in five sizes to fit any size manifold. 30 The attachment of the device to the engine only requires a few moments' work and when it is attached the device has the same appearance as it had before. Furthermore the mixing device being on the inside of the intake manifold requires no extra room at all.

We claim:

1. In a fuel mixing device for internal

combustion engines, a casing open at one end and being provided with a closure at the other end having a series of perforations, the 40 axes of the perforations being at right angles to the axis of the casing, a pair of propellers rotatably mounted within said casing between said closure and the open end of the casing, the blades of said propellers being 45 inclined in opposite directions, and the axes of the propellers being coincident with the longitudinal axis of the casing.

2. The combination with a carbureter outlet pipe having an end flange, of an intake 50 pipe having an end flange arranged to register with the first named end flange, means for securing said end flanges together, a cylindrical casing arranged to enter the end of said intake pipe, said casing having an 55 end flange arranged to extend between said flanges, means for clamping said flanges together, an integral closure at one end of said perforated casing, said closure being provided with a series of perforations, the axes 60 of said last named perforations being at right angles to the axis of the casing, bearing members carried by said cylindrical casing on the interior thereof, a central shaft carried by said bearing members, and a pair 65 of propellers rotatably mounted on said central shaft, the blades of one of said propellers being inclined in an opposite direction from the blades of the other propeller.
